INVENTOR

A. K. WILDERSPIN.

BY *Jack H. Schley*
ATTORNEY

UNITED STATES PATENT OFFICE.

ALFRED K. WILDERSPIN, OF GRAND SALINE, TEXAS.

COMBINED ANDIRONS AND GRATE.

1.127,333.

Specification of Letters Patent.

Patented Feb. 2, 1915.

Application filed October 26, 1914. Serial No. 868,671.

To all whom it may concern:

Be it known that I, ALFRED K. WILDERSPIN, citizen of the United States, residing at Grand Saline, in the county of Van Zant and State of Texas, have invented certain new and useful Improvements in Combined Andirons and Grates, of which the following is a specification.

This invention relates to new and useful 10 improvements in combined andirons and grates.

The object of the invention is to provide a structure including a pair of andirons and a coal grate so arranged that the andirons 15 may be used with or without the grate.

Another feature resides in an adjustable back whereby the depth of the fire box formed on the grate may be varied and a deep or shallow fire maintained.

20 Among other features are the provision of novel joints and connections; and the provision of a swinging bracket for heating and cooking.

A still further object of the invention is 25 to provide a device of the character described that will be strong, durable, efficient, and comparatively simple and inexpensive to produce, also one in which the several parts will not be likely to get out of working 30 order.

With the above and other objects in view the invention has relation to certain 35 novel features of construction and operation, an example of which is described in the following specification and illustrated in the accompanying drawings, wherein:

Figure 1 is a front elevation of a fire place showing my combined andirons and grate therein, Fig. 2 is a plan view of the andirons 40 and grate, Fig. 3 is a transverse vertical sectional view taken on the line $x-x$ of Fig. 1, Fig. 4 is a detail sectional view taken on the line $a-a$ of Fig. 1, Fig. 5 is an isometrical view of component parts forming one of the 45 joints, and Fig. 6 is a detail of the back plate.

In the drawings the numerals 1 and 2 50 designate the front upright members of a pair of andirons which may be of any suitable design. Each member has an aperture 3 near its base which receives the notched tenon 4 of a rearwardly extending supporting bar 5 which has a leg 6 at its rear end. The bars may be detached from the members 1 and 2 and the andirons more conveniently packed and shipped. These parts

form the andirons proper and are all that are required for burning wood. As shown in Figs. 1 and 2 an apertured lug 7 is formed on the rear side of the upright member 1 near its upper end. A swinging bracket 8 is hinged in this lug and shaped to swing into and out of the fire place. In Fig. 3 the parts 7 and 8 are provided on the upright member 2, showing that they may be used on either or both of said members. A kettle or other vessel may be placed on the bracket and swung over the fire.

When it is desired to burn coal a grate is provided. Each supporting bar 5 has a 70 grooved hanger 9 extending along its inner side adapted to receive one end of a grate bar member 10, the latter having depending flanges 11 engaging in the hangers. A front grill panel 12 is mounted upright against 75 the inner sides of the members 1 and 2 and has end posts 14 cast integral therewith. The panel 12 has provision for holding it against longitudinal displacement, as the shoulder 15 shown in Fig. 5.

Each end post 14 has apertures 16 which receive the notched tenons 17 of side panels 18, the latter resting on the bars 5. The front panel 12 and side panels 18 extend above the grate bar member 10 and form a 80 fire box over which the bracket 8 may be swung and in which coal may be burned. Each side panel 18 has a depending lug 19 at its rear end which engages between the member 10 and leg 6 and holds said panel 90 against displacement as will be seen.

A back plate 20 is constructed to rest on the grate bar member 10 and fit between the side panels. This back plate is arranged to be adjusted toward and from the front panel 95 12 whereby the fire box may be made shallow or deep according to the fire desired. The plate has a pair of offset depending lugs 21 on its rear side which engage between the grate bars while the plate rests 100 on one of said bars as shown in Fig. 3. The plate is disposed on incline and projects above the side panels. On each side panel a plurality of bosses 22 are cast on the inside along the top edge and the back plate rests 105 against a pair of these bosses. The spacing of the bosses gives the adjustment to the back plate. The back plate also has a pair of hooks 23, one at each end, which engage over the side panels and prevent spreading 110 of the latter.

It is apparent that when it is desired to

convert the andirons into a grate, it is merely necessary to adjust the bars 5 the proper distance apart, drop the member 10 into place so that its flanges 11 fit in the hangers 9, then place the front panel 12 and the side panels 18, and finally fit in the back plate 20 and adjust the same the required distance from the front panel to give the depth of fire box desired. The parts may be as readily taken apart.

The invention is presented as including such modifications and changes as properly come within the scope of the appended claims.

15. What I claim, is:

1. The combination with a pair of andirons including horizontal supporting bars, of a grate member removably mounted on the bars, a front panel removably mounted 20 on the andirons and abutting the grate member, side panels removably mounted on the supporting bars, and a back plate resting on the grate member and connecting the side panels.
25. 2. The combination with a pair of andirons including supporting bars, of a grate bar member engaging the said supporting bars, a front panel and side panels mounted on the member and bars, and a back plate resting on the grate bar member and engaging the side panels, the side panels and back plate having provision for holding the back plate in adjusted positions with relation to the front panel.
30. 3. The combination with a pair of and-

irons including supporting bars having hangers, of a grate bar member having projections engaging in the hangers of the bars, side panels resting on the bars, a front panel engaged by the side panels, a plurality of 40 spaced bosses projecting from the side panels, and a back plate constructed to engage said bosses in adjusted positions.

4. The combination with a pair of andirons including supporting bars, of a grate 45 bar member engaging the bars, a front panel and side panels mounted on the member and bars, and a back plate having lugs engaging between the bars of the member and provided with hooks engaging over the edges of 50 the side panels.

5. The combination with a pair of andirons including horizontal supporting bars, of a grate member removably mounted on the bars, a front panel removably mounted 55 on the andirons and abutting the grate member, side panels removably mounted on the bars, a back plate resting on the grate member and engaging and connecting the side plates at their rear portions, and means on 60 the side panels for supporting the back plate in adjusted positions whereby the size of the fire space may be varied.

In testimony whereof I affix my signature in presence of two witnesses.

ALFRED K. WILDERSPIN.
